UNITED STATES PATENT OFFICE.

DEAN M. SOLENBERGER, OF CLEVELAND, OHIO, ASSIGNOR TO SIMPLEX PISTON RING COMPANY, OF CLEVELAND, OHIO, A CORPORATION OF OHIO.

PISTON RING.

Application filed December 31, 1925. Serial No. 78,877.

The invention relates to sealing rings of that type in which the ring is rendered both axially and radially expandable respectively by circumferentially slotting and transplitting.

With such constructions some difficulty has been experienced in the formation of a satisfactory joint between the split ends of the ring. It is therefore the object of the present invention to obtain a joint avoiding such defects and to this end the invention consists in the construction as hereinafter set forth.

In the drawings:

Figure 1 is a side elevation of a piston ring shown as developed into a single plane. Figure 2 is an enlarged side elevation of one construction of my improved joint.

Figure 3 is a plan view of the ring in the ring groove.

Figure 4 is a sectional perspective view.

Figures 5 and 6 show modified joint constructions.

The ring A to which my improvements are applied is initially formed of a width greater than that of the ring groove and is then longitudinally slotted preferably with overlapping slots B and C to impart thereto axial resilient compressibility. Thus, when the ring is inserted in its groove D axial tension is exerted sufficient to maintain sealing contact with the side walls of said groove and to conform to any irregularities therein but limited so as not to produce excessive wall friction. It is, however, desirable to increase the radial expansion pressure of the ring by the use of a supplementary expander such as E which may be formed of a corrugated resilient metal ribbon inserted between the inner face of the ring and the bottom of the ring groove.

As previously stated, difficulty has been encountered in providing such a ring with a satisfactory joint. First because the slotting of the ring interferes with the usual lap construction, and secondly because the friction of the expander holds the ring from rotation so that any gap between the ring ends is likely to cause the wearing of a ridge in the cylinder wall. I have, however, avoided such difficulties by the following construction;

As shown in Figures 2, 3 and 4 the ends of the ring on opposite sides of the split are fashioned to form overlapping portions

which are of triangular cross section and which form complementary portions of the full rectangular cross section of the ring. These portions F and G are also slotted for axial resiliency but the slots B' and C' in the respective ends are in different planes. As a consequence each of these slots is sealed by the overlapping triangular portion of the other end as illustrated in Figure 4. Furthermore, each of these slots B' and C' passes through the thicker portion of the triangular cross section thereby avoiding the forming of a weak member that might be easily broken. Also the gap H between the ends of the ring when radially expanded is closed by the large end of the triangular cross section of the other end member thereby avoiding the wearing of a groove in the cylinder wall.

In Figures 5 and 6 modified constructions are shown. Figure 5 shows a simple lapped joint formed by the rabbets I, I' and tongues J, J'. In Figure 6 the split between the ends of the ring is oblique so that there will be an overlapping of such ends even when the ring is fully expanded radially. Both of these constructions will therefore avoid the wearing of a ridge in the cylinder.

In all of the constructions above described the ring A is preferably so slotted that the slots B', C' extending to the ends are in different planes instead of being arranged in the same plane. Also, these slots are less than one-half the length of the other slots B and C thereby shortening the cantilever end portions so that the axial tension exerted thereby is substantially equal to that exerted in other portions of the ring, and the opposite end portions are symmetrical.

What I claim as my invention is:

1. In a transplit sealing ring circumferentially slotted for axial resiliency, a joint formed by end portions having the slots therein arranged in different planes.

2. In a transplit sealing ring circumferentially slotted for axial resiliency, a joint formed by overlapping end portions having slots therein arranged in different planes.

3. In a transplit sealing ring circumferentially slotted for axial resiliency, a joint formed by overlapping end portions of triangular cross section forming complementary portions of the full rectangular cross section.

4. In a transplit sealing ring circumfer-

tially slotted for axial resiliency, a joint formed by overlapping end portions of triangular cross section forming complementary portions of the full rectangular cross section the slots in said end portions being in different planes and in the thicker portion of the cross section.

5. In a transplit sealing ring circumferentially slotted for axial resiliency, a joint formed by overlapping end portions which are symmetrical on opposite sides and equal in tension.

In testimony whereof I affix my signature.

DEAN M. SOLENBERGER.
